UNITED STATES PATENT OFFICE.

JOHN E. SIEGEL, OF CORONA, NEW YORK.

CAR-SEAT.

SPECIFICATION forming part of Letters Patent No. 725,996, dated April 21, 1903.

Application filed February 25, 1902. Serial No. 95,605. (No model.)

To all whom it may concern:

Be it known that I, JOHN E. SIEGEL, a citizen of the United States of America, residing at Corona, in the county of Queens and State

5 of New York, have invented a new and useful Improvement in Car-Seats, of which the following description and claims constitute the specification and which is illustrated by the accompanying sheets of drawings.

10 My invention relates to car-seats, and is designed to provide a very simple construction not liable to get out of order and adapted to allow the shifting of the back from one side to the other of the seat and in the shifting 15 action to move the seat so as to tilt it slightly from front to rear.

In the accompanying drawings, Figure 1 shows an end elevation of a complete seat and back with the supporting-frame. Fig. 2 is a 20 like view with the end plate removed and with the back in reversed position. Figs. 3, 4, 5, 6, 7, 8, and 9 show details of construction.

Screws 12 support the foot-rests 13, while 25 14 is a tube extending longitudinally across the car-seat under the seat-frame, fixed in its position, attached to the wall-end casting preferably by screwing into the threaded hole 15, and at the other end to the aisle-end plate 30 by a bolt 26. The two levers 2, which support the seat-back, oscillate on this tube at its two extremities between the end plates and the seat-frame as a pivot. A distance only equal to the thickness of the lever 2 35 intervenes between the end plates and the ends of the seat-frame. At 16 is shown a portion of the lower surface of the seat-frame toward the front tilted up, as is its position when the seat-back is at rest on the opposite edge.

40 Rocker-plates 3 support the seat-frame and in turn are supported upon the end frames, as indicated at 19, Figs. 2 and 4.

The back is of ordinary construction and has attached to the ends a plate 6, which is 45 provided with a T-shaped slot 10, as shown in Figs. 6 and 8. The arms 2 are pivoted to the back at their extreme upper ends above the center of the back, and there is a further connection between the arms 2 and the back 50 consisting of a link 7, pivoted to the arm 2 at 8 and having a bolt 9 at the opposite end of the link fitting into the slot 10. The T-

shaped upper end of this slot provides locking means in connection with the bolt 9, so that the back may be locked in either position, as shown in Figs. 1 and 2.

55 Assuming the parts of the car-seat to be in the relative position represented in Fig. 2 and that the seat-back is to be shifted to the position represented in Fig. 1, the operator 60 grasps the seat-back at its top, giving it a motion upward and toward the observer's right, at the same time releasing with the other hand the bolt 9 from its position in the depression at the left end of the upper portion 65 of the T-slot 10, whereupon the connecting-link 7 drops by its weight, allowing the bolt 9 to travel down into the lower leg of the slot 10. The movement then proceeds until the seat-back arrives at the position represented in 70 Fig. 1. During this movement the following automatic movements are effected: The toe 22 of the lever 2 pushes against the knee or boss 23 on the rocker-plate 3, causing the seat proper to slide in its bed slightly toward the 75 observer's right. As the lever 2 continues its oscillation the opposite toe 24 engages with the knee or boss on the other rocker-plate, passes the same, and finally rests on the top of the last-mentioned knee or boss. When 80 this has been accomplished, the inclination of the seat proper will have been changed so as to be tilted up toward what will then be the front of the car-seat, the seat-frame, with its cushion, sliding on the rocker-bed to permit 85 of this adjustment. As the operator releases the top of the seat-back from his grasp after the seat-back has reached the position represented in Fig. 1, the bolt 9 is guided by the hand into the depression at the right end of the 90 upper portion of the T-slot 10. The weight of the sitter locks the seat proper and the seat-back in their respective positions thus attained.

95 My improvements dispense with the side rail or arm of the car-seat at the aisle end, thus giving more aisle room and also a maximum of sitting room upon the cushion, while the space intervening between the end of the seat-frame and the end plates of the seat is 100 reduced to a minimum—namely, to the thickness of the levers which support the back—thus rendering unlikely the accidental catching of the clothing. The position of the back

and that of the seat when the latter is occupied is rigid, preventing the possibility of discomfort to the sitter in case one occupying the seat immediately in his rear should place his knees against the back in front of him and cause it to move upward or forward, as is possible in other car-seats, as also similar discomfort produced in the case of other car-seats when one stands behind the seat-back of the sitter and leans against the seat, which is aggravated by sudden stoppage or starting of the car.

Having thus fully described my invention, what I claim, and desire to secure by Letters

15 Patent, is—

1. In combination, with a seat, arms 2 pivoted thereto, a back pivoted to the upper ends of said arms, links pivoted to said arms, end plates secured to said back having vertically-extending slots terminating in L-shaped extensions to one side of the center, and bolts carried by the links engaging said slotted end plates and capable of locking adjustment in the L-shaped extensions, substantially as described.

2. In combination a movable seat-frame, a movable back, arms 2 supporting the same, extensions or toes on the lower ends of the

arms 2 for effecting the movement of the seat-frame in the movement of the back from one position to another and oppositely-located bosses 23 connected with the seat-frame adapted to be alternately engaged by the toes on the ends of the arms 2 substantially as described.

3. In combination a seat-frame, rocker-plates 3 supporting the same, a movable back, pivoted arms 2 supporting said back, extensions or toes on the lower ends of the arms 2, and oppositely-located bosses 23 on the rocker-plates adapted to be alternately engaged by said toes substantially as described.

4. In combination with a movable back, a movable seat-frame, arms 2 supporting the same having substantially T-shaped lower ends forming extensions or toes on opposite sides of said lower ends, and oppositely-located bosses 23 connected with the seat-frame adapted to be alternately engaged by the toes on the ends of arms 2 substantially as described.

JOHN E. SIEGEL.
